UNITED STATES PATENT OFFICE.

HIRAM STEVENS MAXIM, OF LONDON, ENGLAND, ASSIGNOR TO ALBERT VICKERS AND ROBERT R. SYMON, BOTH OF SAME PLACE.

MACHINE-GUN.

SPECIFICATION forming part of Letters Patent No. 321,514, dated July 7, 1885.

Application filed May 27, 1884. (No model.) Patented in England January 3, 1884, No. 606, and in France June 13, 1884, No. 162,737.

To all whom it may concern:

Be it known that I, HIRAM STEVENS MAXIM, a citizen of the United States of America, and a resident of London, England, have invented new and useful Improvements in and relating to Machine - Guns and other Fire - Arms, (for which I have obtained a patent in Great Britain, No. 606, bearing date January 3, 1884, and a patent in France dated June 13, 1884, No. 162,737,) of which the following is a specification, reference being had to the accompanying drawings.

My invention relates to machine or battery guns and other fire - arms, and is chiefly designed to enable the breech mechanism to be operated by the explosive and expansive forces of the gunpowder, or other explosive material employed for firing the gun.

My said invention comprises further improvements in guns of the class described in the specification filed with my application for United States Patent, dated May 2, 1884, No. 130,166.

According to my present invention I sometimes utilize the force of the gases which issue from the muzzle of the gun at each discharge thereof for extracting and ejecting the empty cartridge-case, cocking the hammer, bringing another cartridge into position for firing, and firing the same or preparing the arm for the next discharge, or for effecting one or more of these operations, and (in some cases) storing energy to be subsequently used for effecting the remainder thereof. When a gun is fired, the gases resulting from the explosion of the gunpowder or other explosive material employed issue from the muzzle of the said gun with great velocity, and thereby cause a vacuum or partial vacuum around the muzzle end of the barrel; and one object of my present invention is to provide means whereby the breech mechanism will be operated by the vacuum thus formed.

In the accompanying drawings, Figure 1 is a vertical longitudinal central section of a gun constructed according to my present improvements. Fig. 2 is a plan of the same, partly in section, on the line $x - x$, Fig. 1. Fig. 3 is a transverse section on the line $y - y$, Fig. 1, looking toward the right. Fig. 4 is a transverse

section on the line $y' - y'$, Fig. 1, looking toward the muzzle of the gun.

A is a strong metal frame, which is provided with a lid or cover, A', and which may be mounted on any suitable stand or carriage. 55

B is the barrel, which is fixed in the frame A, and C is the breech-block.

a is a tube or tubular chamber, which is secured to the frame A, and which surrounds the barrel B. The tubular chamber a communicates with another chamber, b, near the rear end of the barrel, and is provided with a sliding portion, a', which can be made to project more or less beyond the muzzle of the gun in such a manner that the escape of the gases therefrom will cause a vacuum or partial vacuum to be formed in the said chambers each time the gun is fired.

c is a piston so fitted in the chamber b that the pressure of the external atmosphere will act thereon when a vacuum is formed, as above described, and will cause the said piston to travel rearwardly in the said chamber. The piston c is provided with two flat rods or bars, c', passing through apertures in the frame A, which serves to guide the said rods. These rods are connected, as hereinafter described, to the mechanism for loading and firing the gun. 75

d is a slotted arm or cross-head, which is fixed to or formed integrally with the breech-block C, and which is provided with a guide-rod, d', extending rearwardly therefrom, and free to slide to and fro in a guide, d'', carried by the frame A. A crank-shaft, e, is carried in bearings e', fixed to the frame A, and is so arranged that the crank-pin e' fits within the slot in the cross-head d. Two arms, f, are fixed to the crank e at right angles thereto, and a pin or rod, f', is passed through these arms and connected by the links f'' to the rear end of the two piston rods c'. When the piston rods are moved rearwardly, the crank e is partially rotated until the crank-pin reaches the point e'', the said crank acting upon the cross-head d so as to draw back the breech-block and the crank-pin traveling in the slot in the said cross-head. The crank - shaft e is made with a square portion to receive a hand-wheel, e'', for operating the breech mechanism by hand. 95 100

g is the extractor, and *h* the sear, which are both pivoted to the breech-block *C*, and *h** is a spring fixed to the said sear and tending to hold the extractor *g* in engagement with the flange of a cartridge when the latter is inserted in the barrel. This spring also tends to hold the sear *h* down so that it will engage with the firing-pin *i*. The said firing-pin passes longitudinally through the center of the breech-block *C*, and is encircled by a spiral spring, *i'*, which tends to press the same forward. The said firing-pin is provided at its rear end with a head, *i''*, which has a knife-edge and a roller, *i'''*, carried by a pin fixed in the said head. A lever, *j*, is pivoted to the cross-head *d*, one end of which lever extends upward between the said knife-edge and the roller *i'''*, and the other end of which extends downward into the path of the crank-pin *e*. These parts are so arranged that during the rearward movement of the cross-head *d* the crank-pin *e* acts upon the lever *j* and causes it to draw back the firing-pin *i* until the sear *h*, which is acted upon by the spring *h**, engages with the head *i''* of the said firing-pin and holds the same in its cocked position. When the sear thus falls into engagement with the firing-pin, the extractor *g* is disengaged from the flange of the cartridge or cartridge-case in the barrel.

The feed-wheels *Q* *Q'* are similar to those described in the specification filed with my said former application for Letters Patent, and are operated in a similar manner, the hooked rod *K'* for removing or transferring the cartridges from the feed-wheel *Q* to the feed-wheel *Q'* being fixed to the cross-head *d*.

The return movement of the piston *c* and parts connected therewith is caused by a volute spring, *k*, like an ordinary clock-spring. This spring is arranged within a cover or case, *k'*, to which one end of the said spring is secured, the other end thereof being secured to the crank-shaft *e*. The cover or case *k'* is attached to the frame *A* by screws, *k''*, passing through the slots *k'''*, and the said cover or case is provided with a handle, *k''''*, so that it can be adjusted in either direction to regulate the tension of the spring *k*. By these means the tension of the spring can be so diminished that after the breech-block and other parts have been moved backward by the force of the explosion the said spring will not cause their return movement. The gun can then be discharged, when desired, by turning the handle *k''''* in the opposite direction.

The operation of this gun is as follows—that is to say: The mechanism is operated by hand until a cartridge is fed into the barrel. The discharge of this cartridge causes the piston *c* to move backward in the chamber *b*, as above described, the breech-block and parts connected therewith moving with the said piston. In this rearward movement the extractor *g* withdraws the empty cartridge-case from the barrel *B* into the uppermost groove of the feed-

wheel *Q'*, and the crank-pin *e*, traveling downward in the slotted cross-head *d*, acts upon the lever *j* and draws back the firing-pin *i*, until the sear *h* falls and its shoulder *h'* engages with the shoulder *i''* of the firing-pin. The downward movement of the sear *h* disengages the extractor *g* from the flange of the cartridge-case. The rearward movement of the hooked rod *K'* draws a cartridge from the uppermost groove of the feed-wheel *Q* into the lowermost groove of the feed-wheel *Q'*, and the projection *C* on the breech-block acts upon one of the teeth of the feed-wheel *Q'*, and causes the partial rotation of the feed-wheels, as described in the specification above referred to. The energy stored up in the spring *k* by the partial rotation of the crank *e* then causes the piston *c* and the breech block and parts connected therewith to move forward. This forward movement causes the feed-wheels *Q* *Q'* to be again partially rotated by the projection *C*, so as to bring a fresh cartridge in line with the barrel, and also to bring a fresh cartridge in the feed-wheel *Q* in line with the lowermost groove of the feed-wheel *Q'*. The breech-block is moreover driven home—that is to say, driven firmly against the breech end of the barrel—and in its forward movement forces the cartridge into the barrel, and at the moment the breech is closed the crank-pin *e* is forced against the end of the sear *h* and pushes the same up, so as to release the firing-pin *i*, which is acted upon by the spring *i'* and discharges the cartridge in the barrel. This movement of the sear also causes the extractor *g* to engage with the flange of the said cartridge. The discharge of the fresh cartridge again operates the mechanism in the manner above described. It will therefore be understood that after the first discharge the fire-arm operates automatically until all the cartridges in the magazine or in the feed-wheels are fired.

It is obvious that my invention may be applied to various descriptions of fire-arms, either for storing energy to be subsequently used for effecting the operations necessary in loading and firing the same, or preparing the arm for the next discharge, or for directly effecting one or more of these operations and storing energy to be afterward used for effecting the remainder of the said operations.

I claim—

1. In a machine or magazine gun, the combination, with the barrel, of a chamber located in proximity to the barrel, with its open end near the muzzle, so that the escape of gases at each discharge will produce a partial vacuum in the chamber, a piston in the chamber adapted to be moved by the air-pressure caused by the vacuum, a sliding breech-block and breech mechanism, and connections between the piston and breech mechanism, whereby the movement of the piston operates the said breech mechanism, as and for the purpose set forth.

2. In a machine or magazine gun, a casing

surrounding the barrel and forming a chamber in the open end of which is the muzzle of the barrel, so that a partial vacuum will be produced in the chamber by the escape of 5 gases at each discharge, and a piston in said chamber adapted to be moved by the air-pressure caused by the vacuum, combined and connected with a sliding breech-block, and the breech mechanism co-operating therewith, 10 whereby the movement of the piston sets in operation the breech mechanism, as and for the purpose set forth.

3. In a machine or magazine gun, a chamber located in proximity to the barrel, and having 15 its open end near the muzzle of the barrel, so that a partial vacuum will be produced in the chamber by the escape of gases at each discharge, and a piston within said chamber adapted to be moved by the air-pressure caused by the 20 vacuum, combined and connected with a sliding breech-block and co-operating breech mechanism, and a device, such as a volute spring, connected to the frame of the gun and to the breech-block, for storing the energy developed by the movement of the piston and forcing it back, and thereby effecting the operation of the gun.

4. In a machine-gun, the combination, with a chamber located in proximity to the barrel, 30 and having its open end near the muzzle, so that a partial vacuum will be produced in the chamber by the escape of gases at each discharge, of piston C, working in the chamber, breech mechanism, and a crank-shaft with a 35 volute spring, k, operatively connected with said breech mechanism, and connections between the piston C and the breech mechanism, whereby a movement of the piston sets the breech mechanism into operation, as set forth.

40 5. In a machine-gun, a chamber located relatively to the muzzle, so that a partial vacuum is produced therein by the escape of gases at each discharge, and a piston working in said chamber, in combination with a slotted cross-head, d, and crank-shaft e, a spring, k, operating on said crank-shaft, the breech-block C, connected with the cross-head, and a hooked arm, K', these parts being constructed and combined for operation in substantially the 45 50 manner described.

6. The breech mechanism consisting of the slotted cross-head d, crank-shaft e, and crank-pin e², in combination with the breech-block, the firing-pin i, (having the head i² formed with a knife-edge, and provided with roller, 55 i³,) and the arm j, pivoted to the cross-head, these parts being constructed and arranged in substantially the manner set forth.

7. In a magazine-gun, the combination, with the breech-block, the cross-head d, and crank-shaft for operating the same, of the arm j, pivoted to the cross-head, the firing-pin i, the sear h, extractor g, and spring h*, carried by the breech-block, and arranged to be operated by the crank-pin e², substantially as set forth. 60 65

8. In a machine-gun of the kind described, the combination, with the breech-block and a crank-shaft for imparting a to-and-fro movement to the same, of a volute spring, k, connected to the crank-shaft, and a cover adjustably secured to the frame of the gun for regulating the tension of said spring, as and for the purpose specified. 70

9. In a machine-gun of the kind described, the combination, with the breech-block, the 75 cross-head d, connected therewith, and the crank-shaft e, for imparting movement to the cross-head, of the volute spring k, connected with the crank-shaft, and the adjustable cover or case k', for varying the tension of the spring, 80 as set forth.

10. In a machine-gun, the combination of a sliding breech-block, the cross-head connected therewith, the crank-shaft E, for imparting movement to the cross-head, a chamber containing a piston connected with the crank-shaft, the said chamber being placed in proximity to the barrel, and having its open end near to the muzzle, and a hand-wheel on the crank-shaft for starting the gun in operation, 85 90 as described.

In testimony whereof I have hereunto signed my name in the presence of two subscribing witnesses.

HIRAM STEVENS MAXIM.
